UNITED STATES PATENT OFFICE.

JAMES L. BREESE, JR., OF CHICAGO, ILLINOIS, ASSIGNOR TO OIL DEVICES CORPORATION, OF CHICAGO, ILLINOIS, A CORPORATION OF ILLINOIS.

PROCESS OF COMBUSTION.

Application filed June 6, 1927. Serial No. 196,690.

My invention relates to a process of and apparatus for burning hydrocarbons, and has for its particular purpose the provision of a mechanism for and a method or process of 5 burning hydrocarbons, preferably in liquid or gaseous form, with a minimum of cracking of the fuel or deposit of carbon. Another object is the provision of means for so burning the fuel as to obtain a maximum 10 heating effect and a minimum clogging or impairing of the mechanism in which the fuel is burned. Another purpose is the provision of such a balance of fuel and air as to produce an intermediate hydroxylated 15 mixture which is not combustible except by the addition of a further supply of air, and may be burned without deposit of free carbon. Another object is the regulation of the respective supplies of fuel and primary and 20 secondary air in such fashion as to insure the formation of an intermediate or hydroxylated incombustible or unburned mixture and to prevent cracking of the fuel.

Other objects will appear from time to 25 time in the course of the specification and claims.

I illustrate my invention more or less diagrammatically in the accompanying drawings, wherein—

20 Figures 1 to 5 each indicate a form of mechanism which may be employed for the practice of my method;

Figure 6 indicates an enlarged sectional view of a portion of Figure 5;

35 Figure 7 indicates another form of device for the practice of my method, wherein means are illustrated for controlling the draft through the stove mechanism and for controlling or preventing down-drafts into 40 the mixing chamber;

Figure 8 is a view on an enlarged scale of the draft control mechanism shown in Figure 7;

45 Figure 9 is a transverse section of a portion of the draft-control; and

Figure 10 is a section on the line 10—10 of Figure 9.

Like parts are indicated by like symbols throughout the specification and drawings.

50 Referring to Figures 1 and 2, A indicates

a generally cylindrical burner housing with a bottom A¹, a top A² and a flue A³ extending from the top. A⁴ is any suitable fuel supply pipe wherein a fuel, for example, a liquid fuel, may be supplied to the bottom of 55 the burner.

Referring primarily to Figure 1, B indicates an air inlet passage, the open top of which, B¹, extends through the top A² of the burner. The bottom of the passage is closed 60 as at B² and the lower part thereof is provided with a plurality of relatively small air inlets B³. B⁴ indicates an enlarged portion of the member B, in communication with the interior thereof, which is pierced by a plurality of air inlet apertures B⁵.

Referring primarily to Figure 2, C indicates the air inlet passage which in this instance admits air through the bottom of the burner as at C¹. C² are a plurality of 70 small air passages along the length of the chamber C. C³ is a laterally expanded portion in communication with the passage member C, and C⁴ are a plurality of air inlet apertures, corresponding to the air inlet apertures B⁵ of Figure 1.

Referring to Figures 3, 4 and 5, D indicates a burner housing of generally cylindrical cross section with the bottom D¹ and the air inlet member D². D³ is the combustion chamber proper, indicated as of generally cylindrical cross section with the generally flat bottom D⁴ and the open top D⁵. D⁶ is a fuel inlet pipe communicating, by the elbow D⁷, with the bottom D⁴ of the combustion chamber and D⁸ is any suitable control valve therefor.

Referring specifically to Figure 3, the walls and bottom of the chamber D³ are closed except for the air inlet passage E through its bottom. E¹ is an enlargement or mushroom associated therewith, provided with the air inlet openings E². E³ is a flange upwardly and inwardly inclined from the cylindrical wall of the housing D and overhanging the upper edge of the member D³ which may, if desired, be inwardly turned as at E⁴ to provide an upwardly and inward inclined air passage E⁵.

Referring to Figure 4 the structure is sub- 100

stantially the same as that shown in Figure 3 except that the member E^{10} , corresponding to the member E , extends to a point above the upper edges of the portions E^3 and E^4 . E^{11} are a plurality of small air inlet passages. E^{12} is an enlargement similar to the enlargement E^1 and is penetrated by apertures E^{14} corresponding to the apertures E^2 .

- 10 Referring to Figures 5 and 6, the wall of the combustion chamber D^3 is pierced by a plurality of small and scattered air inlet apertures E^{20} . The upper edges of the members D and D^3 are connected as at E^{21} .
 15 E^2 indicates a more or less closely spaced row of upwardly and inwardly inclined apertures.

Referring to Figure 7, G indicates an outer drum mounted on legs G^1 and having a closed bottom G^2 with an air inlet G^3 , valve G^{30} controlled for example by the rod G^4 and the handle G^5 . Through any suitable linkage it may control the valve stem G^6 for the valve G^7 in a fuel line G^8 extending from the tank G^9 to the concave bottom G^{11} of the mixing chamber G^{10} . G^{12} indicates a bed of sand or similar finely divided material in the bottom thereof. G^{13} are the primary air apertures and G^{14} are the secondary air apertures of the mixing chamber corresponding to the apertures of the form of Figures 5 and 6.

- H indicates a combustion and radiation member positioned above the mixing chamber, it being provided for example with a cover H^1 and a flue H^2 . H^3 indicates a back draft regulating flap of any suitable light material which is adapted to be drawn normally against the inner abutment H^4 .
 40 Extending from the flue is a lateral passage I . Surrounding the end of said lateral passage or air inlet branch is a split ring I^1 with the outwardly turned opposed terminal flanges I^2 through which pass any suitable securing means, for example the bolts I^3 with the nuts I^4 . I^5 are any suitable spacers.

Secured within the split ring I^1 is any suitable supporting ring J which preferably abuts against the outer end of the lateral inlet member. It may be held in position for example by the transverse pin J^1 which passes through the lugs J^2 in such ring, the opposite ends of the pin J^1 extending outwardly through the wall of the passage or through the split ring which continues it, for example through the relatively extended slots J^3 therein. J^4 is a limiting abutment at one side of the ring, against which abuts one edge J^5 of the damper plate J^6 pivoted for example by the pin J^7 the ends of which terminate within the ring. J^8 is a counter-weight mounted upon the damper plate J^6 , and may be situated for example at the end 35 of the arm or bolt J^9 .

It will be realized that whereas I have described and shown a practical and operative device and method, nevertheless many changes may be made in the size, shape, number and disposition of parts of the mechanism without departing from the spirit of my invention, and that my method may be practiced by a variety of different mechanisms not herein described. I therefore wish my drawings to be taken as in a broad sense illustrative and diagrammatic rather than as limiting me to the particular mechanism or steps therein described and shown.

The use and operation of my invention are as follows:

It is characteristic of my process that the hydrocarbon fuel, whether liquid or gaseous, is burned after the final addition of a secondary supply of air to an intermediate mixture of a hydrocarbon which has been hydroxylated by the admission to it of primary air in quantities sufficient to effect complete or substantially complete hydroxylation. It is important that the primary air so supplied be insufficient to support full combustion, and that the draft be so controlled as to prevent down eddies of air from above which would promote combustion at levels where combustion is not desired. In the devices above described I admit a hydrocarbon, either in liquid form or as a gas, into the lower portion of a mixing or a mixing and combustion zone or member. If a liquid is to be burned, it is gasified by the radiant heat of the combustion going on above it. The gas, or the gasified liquid, rises upwardly, for example through the cylinder A , of Figures 1 and 2, until it reaches the level of the inflowing secondary air. The primary air may be admitted from a central member, as in Figures 1 to 4, or it may be admitted through the wall of a mixing chamber, as in Figures 5 and 6. In either case the cross-sectional area of the holes is determined by the volume of air necessary to effect the hydroxylation of the hydrocarbon, and sufficient air should be supplied to effect the complete or virtually complete hydroxylation, without at the same time supplying sufficient additional air to support combustion.

The distribution of the apertures is preferably such as to effect a relatively complete mixture of the primary air with the hydrocarbon, so that the entire volume of the hydrocarbon is hydroxylated. To effect this result, and to prevent the addition of such an excess of air at a given point as might support local combustion, I prefer to employ a large number of small, scattered apertures. Also in many forms of my device, it is important that small apertures be used in order that the cross-sectional area and strength of the individual jets of air

be insufficient to cause down-drafts and turbulence or to effect the upward rise of the gas or gasified mixture.

The effect of the addition of the primary air supply is to cause the formation of addition compounds, for example aldehydes, which, on further heating, will decompose without deposit of carbon. These mixtures can then be burned off by the addition of 10 the secondary air supply. In combustion, in a burner of the type herein disclosed, there is always a race between combustion by hydroxylation and combustion by cracking and it is the purpose of my method 15 and device to so control conditions of air and fuel supply and to so control the intermediate mixture and the fuel product, as to insure that combustion by hydroxylation will win the race. Draft control and 20 back-draft prevention may also be important to maintain the desired combustion conditions.

Assuming the completion of the hydroxylated mixture, which continues its upward 25 movement through the mixing zone, I provide a secondary air supply, which may be introduced through a mushroom, as in Figures 1, 2 and 4 or through the wall of the mixing chamber, as in Figures 5 and 6, 30 or over the top of the wall of a mixing chamber, as in Figures 3 and 4. It is essential that the secondary air be sufficient in volume to support the complete combustion of all of the hydroxylated mixture. 35 It is not essential that a complete mingling of the hydroxylated mixture and the secondary air take place, although such mingling may take place, since combustion may occur along the zone or plane of meeting 40 of the secondary air and the mixture. Where the secondary air is admitted through apertures such as B³ or C⁴, the combustion may take place along the jets of inflowing secondary air. Where the secondary air is directed upwardly and inwardly into or over the mixture, as in Figures 45 3, 4 and 6, a cone of flame may be formed the center of which, if the fuel supply is sufficient, flares up into the interior 50 of the furnace or combustion chamber.

In a typical application of my process to the burning of a liquid fuel, as in Figure 1, the fuel may be supplied along the pipe A⁴ to the bottom A¹, where it is exposed to 55 the radiant heat of combustion taking place in the upper portion of the member A. As the liquid is vaporized and gasified it rises and is mixed with a primary air supply entering through the apertures B³. This air 60 supply may be controlled, either through varying the size of the passage B³ or their number, or otherwise, to provide an air supply sufficient for the substantially complete hydroxylation of the gaseous fuel. Not only 65 is there a mechanical mixture of this air

supply with the gaseous fuel, but the oxygen unites with the hydrocarbon and forms compounds, under the influence of the heat of the adjacent combustion, in which are combined carbon molecules which might 70 otherwise be deposited in the form of soot or might be discharged as smoke. These new compounds are in the main such that, when they are further heated they decompose or burn without the deposit of carbon. 75 The mixtures so formed vary, depending upon the particular hydrocarbon or mixture of hydrocarbons burned, but they have this in common, that the gasified hydrocarbons join with the oxygen so introduced to form 80 chemical compounds which, upon further combustion, do not deposit any substantial proportion of carbon. The mixtures so formed rise upwardly past the large portion B⁴, or, in the case of Figure 2, C³, and receive the additional secondary air supply 85 through the apertures B³ or C⁴. Sufficient oxygen is thus supplied to support the combustion of the completed mixture and combustion takes place, in the main, above the 90 level of admixture of the secondary air supply.

Figures 3, 4 and 5 indicate simply varying structures for accomplishing the same general result. As regards Figure 3 the primary air is supplied through the apertures E² and the secondary air through the annular passage E⁵. As regards Figure 4 the primary air comes through the passages E¹¹ and the secondary air is directed both 100 through the passage E⁶ and the passages E¹⁴, providing a peculiarly complete admixture of a secondary air supply for supporting combustion of the previously hydroxylated mixture. 105

In the form of Figures 5 and 6 the primary air enters through the passages E²⁰ and the secondary air is directed upwardly and inwardly through the somewhat larger passages E²². 110

In the forms of my device shown in Figures 3, 4 and 5, I prevent the formation of down-drafts or eddy currents which might affect the delicate balance of my process by delivering the secondary air supply both 115 upwardly and inwardly. It will be realized that I do not wish to be limited to any such specific practice, but it is described as a practical solution of one phase of my problem.

It will be realized that air is shown as 120 admitted by natural draft but I do not wish to be limited to any particular mechanism or method of introducing either the primary or the secondary air supply.

Referring to Figures 5 and 6, in employing this type of mechanism, I find it preferable to so proportion the apertures that the total cross-sectional area of the upper row, through which the secondary air is admitted, is greater than the total cross-sec- 125 130

tional area of all the rest of the apertures through which the primary air supply is admitted. It may be two or three times as great and may even be many times as great.

5 In the forms of Figures 3 and 4 a similar relation may be maintained by the proportion of the inlet E^3 in relation to the total cross-sectional area of the smaller apertures.

The following dimensions are applicable 10 to a typical burner for carrying out my process. I may employ a burner with a mixing drum having a diameter of ten inches and a depth of ten inches. Scattered about the lower portion of the walls of said drum, 15 and preferably evenly distributed, starting at a distance of 1.5 inches from the bottom and stopping at a distance of 1.5 from the top, are approximately 100 primary air apertures the total area of which amounts to 20 .75 square inch. Arranged along the upper rim of the drum .5 inch below the top is a close row of 130 secondary air apertures. The total area of these apertures is 1.24 square inch.

25 Referring to the use of the damper plate or swinging valve, it may be positioned in the flue or in an air inlet thereto, as herein shown, with the pivot pin in generally horizontal position. When so positioned the 30 counterweight holds the plate in the position shown in Figure 9, with its upper portion engaging the abutment of the ring. The damper or swinging valve, when so positioned, will relatively strongly resist the 35 tendency of air to displace it. When it is desired to vary the resistance of the damper or swinging valve to the passage of air or gases, it is necessary merely to rotate the 40 holding ring by moving the end or ends of its pin. When so rotated, the axis of the valve is moved from the horizontal position, and the closing and air resisting effect of the counterweight is thus reduced in direct ratio to the displacement of such axis 45 from the horizontal. Theoretically, when the axis is vertical, the counterweight has no effect whatever in resisting air passage, and any desired resistance to air or gas passage may be obtained by rotation of the holding 50 ring within the limits of its movement. Furthermore the counterweight may be shifted or adjusted as to its distance from the valve, by rotation of the nuts on the pin J^3 . It will be realized that I may by the use of the 55 above described mechanism, so adjust the draft of a given burner or furnace as to obtain the conditions of air inflow particularly adapted for the carrying out of my method.

60 The pivoted flap H^3 , which is normally drawn against its abutment by the draft up the flue, is so light and so lightly pivoted as to blow out and relieve the pressure within the stove when for any reason there is a

down-draft into the body of the stove. 65 This prevents back-drafts and eddies down into the mixing chamber and materially reduces the risk of disturbances of the balance of combustion and the regular order of steps elsewhere herein described. 70

In the form of my device shown for example in Figure 7 the mixture which is hydroxylated in the mixing pot and which rises upwardly past the level of the secondary air apertures G^{14} is in effect enveloped 75 by an envelope or layer of secondary air which in practice flows upwardly with and about the upwardly rising stream of the hydroxylated mixture. This result is obtained by the upward inclination of the secondary air apertures whereby the pencils of air so directed instead of coming directly across the path of upward movement of the mixture are readily deflected upwardly by the mixture and form a layer or jacket or envelope of secondary air surrounding the primary mixture. In practice combustion 80 takes place at the meeting or mixing zone of the primary mixture and its envelope of secondary air. 90

I claim:

1. The process of burning a hydrocarbon which includes providing a gaseous hydrocarbon, hydroxylating the hydrocarbon while maintaining it substantially throughout at 95 a temperature below that of active combustion, admitting to the hydroxylated hydrocarbon a secondary oxygen supply, and burning the hydroxylated hydrocarbon after such admittance. 100

2. The process of burning a hydrocarbon which includes admitting a liquid hydrocarbon to a mixing zone, gasifying such hydrocarbon, while in said zone, by the heat of combustion, causing the gasified 105 hydrocarbon to rise upwardly from the level of the liquid hydrocarbon, and adding to it, as it rises, and mixing thoroughly with it, a primary air supply sufficient to effect its substantially complete hydroxylation while 110 maintaining it substantially throughout at a temperature below that of active combustion, causing the hydroxylated mixture to rise upwardly above the level of admission of the primary air supply and admitting to 115 it, at a higher level, a secondary air supply sufficient to support its complete combustion, and there burning the final mixture.

3. The process of burning a hydrocarbon which includes maintaining a supply of 120 liquid hydrocarbon, gasifying such hydrocarbon by the radiant heat of combustion, maintaining a mixing zone above said liquid hydrocarbon and delivering into said mixing zone, into the gasified hydrocarbon upwardly rising therethrough, a primary air supply sufficient to effect its substantially 125 complete hydroxylation while maintaining

it substantially throughout at a temperature below that of active combustion, admitting to the hydroxylated mixture, after it has risen above the zone of mixture with the primary air a secondary air supply, and burning the fuel mixture after the admission of the secondary air supply.

4. The process of burning a hydrocarbon which includes maintaining a supply of liquid hydrocarbon, gasifying such hydrocarbon by the radiant heat of combustion, maintaining a mixing zone above said liquid hydrocarbon and delivering into said mixing zone, into the gasified hydrocarbon upwardly

15 rising therethrough, a primary air supply sufficient to effect its substantially complete hydroxylation while maintaining it substantially throughout at a temperature below that of active combustion, such air supply being admitted in a large number of scattered jets, admitting to the hydroxylated mixture, after it has risen above the zone of mixture with the primary air a secondary air supply, the secondary air supply being admitted in an even larger number of larger jets, and burning the fuel mixture after the admission of the secondary air supply.

5. The process of burning a hydrocarbon which includes maintaining a supply of liquid hydrocarbon, gasifying such hydrocarbon by the radiant heat of combustion, maintaining a mixing zone above said liquid hydrocarbon and delivering into said mixing zone, into the gasified hydrocarbon upwardly rising therethrough, a primary air supply sufficient to effect its substantially complete hydroxylation while maintaining it substantially throughout at a temperature below that of active combustion, such air supply being admitted in a large number of scattered jets, admitting to the hydroxylated mixture, after it has risen above the zone of mixture with the primary air a secondary air supply, the volume of the secondary air supply substantially exceeding the volume of the primary air supply, and burning the fuel mixture after the admission of the secondary air supply.

6. The process of burning a hydrocarbon which includes maintaining a supply of liquid hydrocarbon, gasifying such hydrocarbon by the radiant heat of combustion, maintaining a mixing zone above said liquid hydrocarbon and delivering into said mixing zone, into the gasified hydrocarbon upwardly rising therethrough, a primary air supply sufficient to effect its substantially complete hydroxylation while maintaining it substantially throughout at a temperature below that of active combustion, admitting to the hydroxylated mixture, after it has risen above the zone of mixture with the primary air a secondary air supply, the secondary air supply being directed upwardly and inwardly into the normal path of up-

ward movement of the hydroxylated mixture.

7. The process of combustion which includes providing a gaseous hydrocarbon, hydroxylating such hydrocarbon while maintaining it substantially throughout at a temperature below that of active combustion, conveying such hydroxylated hydrocarbon, from its zone of hydroxylation to a zone of combustion, admitting air to the hydroxylated hydrocarbon at or near such zone of combustion and burning the hydroxylated hydrocarbon.

8. The process of burning a liquid hydrocarbon which includes gasifying said liquid hydrocarbon by the heat of combustion, hydroxylating the gasified hydrocarbon by the admission of a primary air supply thereto while maintaining it substantially throughout at a temperature below that of active combustion, conveying the hydroxylated hydrocarbon from its zone of hydroxylation to a zone of combustion, admitting a secondary air supply to the hydroxylated hydrocarbon at or near such zone of combustion, and burning the hydroxylated hydrocarbon.

9. The process of burning a hydrocarbon which includes providing a gaseous hydrocarbon, hydroxylating such hydrocarbon and forming a generally homogeneous hydroxylated mixture while maintaining it substantially throughout at a temperature below that of active combustion, admitting air to such homogeneous hydroxylated mixture, after its hydroxylation, and burning the hydroxylated hydrocarbon after such admittance of air.

10. The process of burning a hydrocarbon which includes providing a gaseous hydrocarbon, hydroxylating the hydrocarbon while maintaining it substantially throughout at a temperature below that of active combustion, admitting a secondary oxygen supply, enveloping the hydroxylated mixture with said secondary oxygen supply, and burning the hydroxylated hydrocarbon after such envelopment.

11. The process of burning hydrocarbon which includes maintaining a supply of liquid hydrocarbon, gasifying such hydrocarbon by the radiant heat of combustion, maintaining a mixing zone above said liquid hydrocarbon and delivering into said mixing zone, into the gasified hydrocarbon upwardly rising therethrough, a primary air supply sufficient to effect its substantially complete hydroxylation while maintaining it substantially throughout at a temperature below that of active combustion, enveloping the hydroxylated mixture, after it has risen above the zone of mixture with the primary air, with a secondary air supply, and burning the fuel mixture after such envelopment.

12. The process of burning hydrocarbon

which includes providing a gaseous hydrocarbon, hydroxylating such hydrocarbon and forming a generally homogeneous hydroxylated mixture while maintaining it substantially throughout at a temperature below that of active combustion, providing a secondary supply of air and enveloping such

homogeneous hydroxylated mixture therewith, after its hydroxylation, and burning the hydroxylated hydrocarbon after the initiation of such envelopment. ¹⁰

Signed at Chicago county of Cook and State of Illinois, this 1st day of June, 1927.

JAMES L. BREESE, JR.
